UNITED STATES PATENT OFFICE.

JOHANNES CHRISTIAAN WEGERIF, OF LONDON, ENGLAND.

ROLLER-MILL FOR CRUSHING AND GRINDING.

SPECIFICATION forming part of Letters Patent No. 684,148, dated October 8, 1901.

Application filed April 26, 1901. Serial No. 57,584. (No model.)

To all whom it may concern:

Be it known that I, JOHANNES CHRISTIAAN WEGERIF, engineer, a subject of the Queen of the Netherlands, residing at 45 Woburn Place, London, England, have invented a new and useful Improvement in Roller-Mills for Crushing and Grinding, of which the following is a specification.

My invention relates to an improved roller-mill for crushing and grinding, which consists, essentially, in the combination of internal and external revolving grinding-surfaces having their axes of revolution oblique the one to the other and in different planes, so that the planes of revolution will be mutually oblique and a disruptive as well as a crushing action will be produced, the one surface being formed by the interior of a revolving ring and the other by the exterior of a revolving roller working within the ring.

Reference is to be had to the accompanying drawings, wherein is illustrated one form of my improved mill comprising a crushing-ring and a revolving roller, both adapted to rotate about horizontal axes which lie in vertical planes oblique to one another, the roller being mounted in a lever-frame loaded by spring-pressure.

In the drawings, Figure 1 is a plan view, and Fig. 2 a side elevation, of the mill, both views being partly in section.

It is, however, to be distinctly understood that I do not limit myself to the particular form or arrangement of parts herein illustrated.

Referring to the drawings, *a* is the pressure-roller, carried by a shaft *b*, journaled in bearings *c* in the two side members *d* of a V-shaped lever-frame fulcrumed at *e e* to the bed-plate *f* and loaded by the pressure of a spring or springs *g*, applied to the point of convergence of the two side members *d* of the lever, the springs *g* being confined between the lever and an adjustable nut *h*, screwing upon a rod *i*, passing through the spring and anchored to the bed-plate *f*, the downward motion of the lever-frame being limited by a stop formed of packing-blocks *j*, changeable to regulate the initial setting of the roller and allow for wear of the roller and ring. The side members *d* of the lever-

frame may be tied together by a cross-stay, such as *k*.

l is the ring, which is provided with a renewable liner *m*, whose interior periphery 55 forms the grinding-surface of the ring, the liner *m* being seated within the ring, so as to revolve therewith as one, and being prevented from endwise displacement therein by a shoulder *n* or other suitable means. 60

The ring *l* is mounted to revolve in a stationary bearing *o*, preferably formed, as shown, by an annular casting or plumber-block carried by the bed-plate *f*, there being, if desired, a set of antifriction-rollers interposed, as at *p*, between the revolving ring *l* and the bearing *o*, while the endwise thrust of the ring *l* (due to the disruptive stress caused by the obliquity of the roller and ring axes) may be resisted by a set of bearing-balls, as at *q*, running in V-grooves formed in adjacent faces of the bearing *o* and of a flange *r* on the revolving ring *l*. Instead, however, of the ring *l* being mounted to revolve within an annular bearing, as shown, it might 75 be otherwise supported rotatably—as, for example, upon external guide-sheaves mounted in fixed bearings, the end thrust of the ring being resisted by other sheaves suitably applied. 8c

The ring *l* is shown as being driven by rope bands running upon the grooved periphery *s* of the end flange *r* of the ring and the roller *a* by a belt running upon a fly-wheel pulley *t*, keyed upon the shaft *b*. The endwise 85 thrust transmitted by the shaft *b* may be resisted by collars *u* on the latter taking against the ends of the bearings *c* in which the shaft rotates, bearing-balls being, if desired, interposed to lessen the effect of friction. For 90 the same purpose a thrust-bearing, such as indicated in Fig. 2, may be provided on that member *d* of the lever-frame toward which the thrust of the shaft *b* is directed, a set of antifriction-balls being interposed, as at *v*, 95 between the end of the shaft and a thrust-block *y*, supported by the bearing and adjusted by means of a set-screw, as at *w*.

It is desirable that the side members *d* of the lever-frame should converge symmetrically, as shown in Fig. 2, so that the axis of the spring guide-rod *i*, and therefore the point

- of application of spring-pressure to the lever-frame, may lie in the central transverse plane of the roller *a*. It will be evident that by this arrangement the pressure applied to the 5 roller *a* will be uniformly distributed throughout the length of the roller and that in consequence of the lever-frame being fulcrumed in fixed bearings at *ee* the roller will be prevented from canting in the event of an excess 10 of material being fed in toward either end of the line of contact or bite *xx* between the roller *a* and liner *m*.
- The axes of both the roller *a* and ring *l* are, as already stated, shown in the example illustrated 15 as being horizontal; but in certain cases it may be desirable to arrange the axis of the roller *a* or that of the ring *l*, or even both these axes, at an inclination to the horizontal. Further, in order that a straight and 20 substantially horizontal line of "bite" may be maintained between and continuously across the whole width of the grinding-surfaces of the roller and ring the periphery of the roller *a* is shown as being slightly con- 25 cave and that of the liner *m* slightly convex, each in a direction parallel to its own axis. The grinding-surface of the ring-liner *m* might, however, be cylindrical, in which case the form of the roller *a* must be slightly bar- 30 reled or bellied, so that the line of bite between the ring and roller may be continuous, or the roller *a* might be cylindrical and the surface of liner *m* convex, or the roller *a* might be barreled or bellied and the surface 35 of liner *m* concave, the form of the grinding-surfaces in every case being such as to preserve a continuous line of bite between the ring and roller. Similarly the degree of obliquity between the planes in which the 40 ring and roller axes lie is shown as being about fifteen degrees; but this might be varied, in which case also the form of the grinding-surface of the ring or of the roller, or of both, would need to be correspondingly varied 45 in order to maintain a continuous line of bite.

In the example illustrated the roller *a* is shown as bearing directly upon the lowermost part of the ring; but it might bear 50 against the ring toward one side of the vertical axial plane of the ring, and in that case if the axis of the roller is horizontal the axis of the ring would need to be inclined, or vice versa.

- 55 In any case the mutual relative positions of the ring, the roller, and the lever-fulcrum may be so arranged as to produce a kind of

wedging action between the roller and ring, in addition to the direct pressure due to the weight of the roller and the load on the lever-frame. 60

The material to be ground would be fed into the ring in advance of and as close as practicable to the line of bite of the roller and ring and after passing between the grinding-surfaces would be discharged from the ring in any convenient manner. 65

I claim—

1. A mill for crushing and grinding, consisting of a roller rotating within and in surface contact with a revolving ring, the axes of the roller and ring being oblique to one another and in different planes, and the acting external surface of the roller and the internal surface of the ring being mutually of such relative configuration that a continuous line of bite between the surfaces of the roller and ring will be maintained notwithstanding their mutual axial obliquity, and a disruptive as well as a crushing action will be produced, as specified. 70

2. A mill for crushing and grinding, consisting of a roller rotating within and in surface contact with a revolving ring, the axes of the roller and ring lying in different horizontal planes and in different vertical planes oblique to each other, and the acting external surface of the roller and the internal surface of the ring being mutually of such relative configuration that a continuous line of bite 85 between the surfaces of the roller and ring will be maintained notwithstanding their mutual axial obliquity, and a disruptive as well as a crushing action will be produced, as specified. 90

3. A mill for crushing and grinding, consisting of a roller journaled in a pressure-lever frame, the roller being adapted to revolve within and in surface contact with a revolving ring, the axes of the roller and ring being oblique to each other and in different planes, and the contacting surfaces of the roller and ring being mutually of such relative configuration that a continuous line of bite between the contacting surfaces will be maintained and a disruptive as well as a crushing action will be produced in consequence of the mutual obliquity of the planes of revolution of the roller and ring. 95

JOHANNES CHRISTIAAN WEGERIE.
